UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

SHEET-CONTROL MECHANISM.

Application filed May 3, 1924. Serial No. 710,757.

This invention relates to sheet control mechanism which is adapted for use in printing presses and the like.

One object of the invention is to provide simple and efficient means to prevent feeding of a sheet after the press is tripped, whether tripped manually or automatically.

Another object is to provide sheet control mechanism for use in printing presses adapted to meet the various requirements under service conditions.

These and other objects are accomplished by means of the arrangement disclosed on the accompanying sheets of drawings, in which

Figure 1 is a fragmentary side elevation of a printing press embodying my invention;

Figure 2 is an enlarged detail view showing such control parts in side elevation; and Figure 3 is a fragmentary top plan view, parts being shown in section, and taken in the plane of line 3—3 of Figure 2.

The various novel features of the invention will be apparent from the following description and drawings, and will be particularly pointed out in the appended claims.

Referring to the drawings, it will be noted that the invention is disclosed in connection with a printing press having a main frame 10 in which a rotatably mounted impression cylinder 11 is supported, sheet material being fed from a feed pile 12, down over a feed board 13 to a front guide (not shown) preparatory to being gripped by the grippers on the cylinder 11.

If for any reason the press is tripped, it is important that further feeding of sheets should be stopped whether the press is tripped as a result of poor registering by means of the arrangement disclosed in my co-pending application, Serial No. 710,755 filed May 3, 1924, or tripped manually, as disclosed in said same application, or tripped as a result of plural sheet detection which will be more fully described in this present application.

As will be pointed out more fully herein-after, whenever the press is tripped an automatically actuated sheet clamp or holding or stopping member 15 will be liberated and pressed into engagement with a sheet of material 16 being fed over the feed board 13 and between the latter and said clamp 15. The clamp 15 takes the form of a suitably shaped rod which is adjustably secured in

a bracket 17 formed on a lever arm 18 mounted on a rock shaft 19. The lever arm 18 rests upon an arm 20 secured to a rock shaft 21 to which also is secured an arm 22 pivotally connected at 23 to a link 24 also pivotally connected at 25 to an arm 26 secured to a shaft 27 which also has secured to it a latch 28, normally pressed for rotation in a counterclockwise direction, as viewed in Figure 2 of the drawings, by a spring 29. From the connections thus far described, it will be appreciated that if the latch 28 is freed from a locking dog 30 which normally holds it against movement, the spring 29 will rotate the latch 28 in a counterclockwise direction for raising the lever arms 20 and 18 and forcing the clamp 15 into engagement with a sheet of material 16, clamping the latter between the clamp and feed board 13 with sufficient force to prevent further progressive feeding of said sheet.

The locking dog 30 is pivotally connected to a link 31 which in turn is pivotally connected at 32 to a bell crank lever 33 which is pivotally connected to another link 34 connected to the main trip lever 35 through which the press is tripped. As mentioned hereinabove, whenever the press is tripped regardless of the cause of the tripping, the lever 35 is depressed, withdrawing the locking dog 30 for permitting positive application of the clamp 15 to a fed sheet of paper. As stated before, the tripping of the press may be the result of poor front register, or as a result of a manual tripping of the press through a pedal 36 and, among other things, as a result of double or thick sheet detection as will now be described.

The sheet material is fed from the pile 12 down through a tapering throat 37 formed by relatively adjustable members 38 and 39 which may be supported in any suitable way and in a manner to vary the opening through the throat. Preferably the throat member 39 is provided with a slot 40 for the reception of a detector member 41 having an upper arc shaped surface which preferably lies in the same plane as the top of the throat member 39 at the point where the detector member is normally located, so that sheet material passing over and in engagement with the throat member 39 also will pass over and engage the arcuate surface of the detector 41. The detector 41 will remain in the position shown in Figure 2 so

long as sheet material of the proper thickness is fed through the throat. In other words, sheet material of a total given thickness will be permitted to pass through the 5 throat 37 and any sheet material over such total thickness, whether one or more sheets, will not be permitted to be fed freely through said throat to the cylinder, but will cause a clockwise rotative movement of the 10 detector member 41, resulting in the clamping of the fed sheet between the clamp 15 and the feed table 13. The detector 41 is suitably pivotally connected at 42 to a suitably supported bracket 43 and is limited in 15 its counterclockwise movement by engaging a stop 44 on said bracket. Normally, a laterally extending lug 45 formed on the detector 41 is engaged by an arm 46 of a two- 20 armed lever 47 pivotally supported upon a shaft 48, the second arm 49 being pivotally connected at 50 to a link 51 having one end pivotally connected to one arm 52 of a bell 25 crank lever pivoted at 53, the other arm 54 of said bell crank lever having a roller 55 adapted to ride on a suitably actuated and 30 timed cam 56 and under certain predetermined conditions pass into a depression 57 in said cam for the purpose of withdrawing the locking dog 30 for causing an application 35 of the clamp 15. In this connection it will be noted that also mounted upon the shaft 48 is an arm 58 which engages the upper end of the locking dog 30 for disengaging the latter from the latch 28 for 40 permitting the clamping action referred to. The lever arm 52 is pressed by a spring 59 in a clockwise direction, as viewed in Figure 1, for the purpose of holding the roller 55 against the cam 56 and for pressing 45 the locking dog 30 out of engagement with the latch 28 when the roller 55 is presented to the cam recess 57 and is permitted to move thereinto. This results only when the plural sheet detector 41 has been rotated in 50 a clockwise direction, as viewed in Figure 2, for liberating the lever arm 46 from the lug 45. Through the connections described it is apparent therefore, that when more than a single sheet of material is fed 55 through the throat 37, or when a single sheet of material of excessive thickness is fed therethrough, the detector 41 will be rotated in a clockwise direction, thereby liberating lever 46 for permitting the spring 59 through connections described, to throw the locking dog 30 out of locking engagement

with the latch 28 for permitting the clamping member 15, through the spring 29, to be positively forced down into clamping engagement with a fed sheet, preventing further feeding movement thereof. 60

It is my intention to cover all modifications of the invention falling within the spirit and scope of the following claims. 65

I claim:

1. In a printing press, the combination of a press tripping member, a sheet clamping member for preventing feeding of a sheet under abnormal sheet feeding conditions, a latch operatively connected to said press tripping member and normally holding said sheet clamping member in an inoperative position, and plural sheet detector means operative upon said latch for permitting said clamping member to exert a clamping 75 action and for causing the tripping of the press upon the occurrence of such abnormal sheet feeding conditions. 80

2. In a printing press, the combination of a press tripping member, a sheet clamping member for preventing feeding of the sheet under abnormal sheet feeding conditions, means operatively connected to said press tripping member and normally holding the said sheet clamping member in an ineffective 85 position, and plural sheet detector means operative upon said first mentioned means for permitting said clamping member to exert a clamping action and for causing the tripping of the press upon the occurrence of ab- 90 normal sheet feeding conditions. 95

3. In a printing press, the combination of a sheet clamping member for preventing feeding of a sheet under abnormal sheet feeding conditions, a latch operatively connected to said press tripping member and normally holding said sheet clamping member in an ineffective position, a cam with a depression therein, a member pressed against said cam to follow the contour thereof, and 100 a plural sheet detector normally preventing the cam engaging member from passing into its depression but which upon the occurrence of abnormal sheet feeding conditions releases said cam engaging member for permitting movement of said latch to trip the press and for permitting said clamping member to exert a clamping action. 105

Signed at Chicago, Illinois, this 8th day of April, 1924.

JOSEPH R. BLAINE.
